UNITED STATES PATENT OFFICE

119,774

DESIGN FOR AN INJECTOR BODY

Walter H. Tinker, Wadsworth, Ohio, assignor to
The Ohio Injector Company, Wadsworth, Ohio,
a corporation of Ohio

Application January 11, 1940, Serial No. 89,401

Term of patent 14 years

To all whom it may concern:

Be it known that I, Walter H. Tinker, a citizen of the United States, residing at Wadsworth, in the county of Medina and State of Ohio, have invented a new, original, and ornamental Design for an Injector Body, of which the following is a specification, reference being had to the accompanying drawing, forming part thereof.

Figure 1 is a side elevational view of an injector body showing my new design.

Fig. 2 is a side elevational view thereof looking at the opposite side from that shown in Fig. 1.

Fig. 3 is an end elevational view thereof taken from the left of Fig. 1.

Fig. 4 is an end elevational view thereof taken from the right of Fig. 1.

Fig. 5 is a top plan view thereof, and
Fig. 6 is a bottom plan view thereof.

What I claim is:

The ornamental design for an injector body, as shown.

WALTER H. TINKER.
